UNITED STATES PATENT OFFICE.

ALBERT B. CLISSON, OF SYRACUSE, NEW YORK, ASSIGNOR TO THE PROSPERITY COMPANY INC., OF SYRACUSE, NEW YORK, A CORPORATION OF NEW YORK.

NECKBAND CLAMP FOR SHIRT-PRESSING MACHINES.

Application filed March 8, 1926. Serial No. 93,075.

This invention relates to shirt pressing machines and particularly to neck band clamps for such machines, which neck band clamp is particularly simple in construction, is composed of a minimum number of parts and is highly efficient and durable in use.

The invention consists in the novel features and in the combinations and constructions hereinafter set forth and claimed.

In describing this invention reference is had to the accompanying drawings in which like characters represent corresponding parts in all the views.

Figure 1 is a plan view of this neck band clamp, the contiguous part of the pressing table or buck of a pressing machine being shown.

Figure 2 is an enlarged side elevation of the parts seen in Figure 1.

Figure 3 is an elevation on a reduced scale of this neck band clamp showing the same applied to the buck of a pressing machine.

Figure 4 is a view similar to Figure 3 showing the neck band clamp in its open or inoperative position.

This neck band clamp comprises, generally, a body having a curved surface against which the front of the neck band is clamped, a clamp mounted to have a pivotal movement into and out of position opposed to said surface and also having rectilinear or clamping movement toward and from said surface, an operating member for effecting the rectilinear movement and means for preventing pivotal movement during the rectilinear movement or the initial portion of the rectilinear movement before the clamp comes firmly against the neck band.

1 designates the buck of the press to which the neck band clamp is applied.

2 is the body of the neck band clamp, the body being secured to the buck in any suitable manner. The body is provided with an arc shaped or curved surface 3 against which the front of the neck band is clamped.

4 designates the clamping member as a whole, that here shown being in the form of a resilient loop extending around the surface 3 and pivoted at its rear ends to move toward and from the buck and also having rectilinear movement toward and from the surface 3. As here shown the band or loop portion 5 of the clamp is secured at its rear end to bearings 6 which are mounted upon a pivot pin 7, which in turn is mounted in a

bearing in an operating member to be presently described. One of the bearings is formed with a weighted arm 8 which tends to move the loop upwardly on its pivot away from the buck and out from in front of the face 3 out of the body.

9 is the operating member in which the pivot 7 is mounted, this operating member being pivoted at 10 to the lower end of a carrier as a link 11 yieldingly connected to the body through a cushioning spring so as to permit a full throw of the handle or operating member when the loop of the clamping member is tightly engaged with the collar band, that is when the pivots 7 and 10 are nearing a horizontal plane. The axis of the operating member is in the plane of the face 3.

The pivot 10 as here shown is provided with a toggle or stop joint, by means of a lug 12 on the link 11 and an arm 13 on the operating member 9 coacting therewith, which prevents said operating member from being moved downwardly beyond a horizontal plane.

The link or carrier 11 is here shown as pivoted at 14 at its upper end to a bracket 15 extending upwardly from the body, and a compression or buffer spring 16 is interposed between the link 11 and the bracket 15.

The clamping member 4 also comprises means for operating the loop 4 so that when the loop is being moved into operative position, it is opened or spread to slip over the collar band. This spreading means here shown as outwardly pressing springs 17 fixed at their rear ends to the bearings 6 and pressing at their outer ends against the inner faces of the ends of the loop 5.

In operation the handle 18 of the operating member 9 normally stands upwardly at an oblique angle indicated in dotted lines Figure 2, and the pivot 7 is also elevated slightly and the loop is in the elevated position indicated in dotted lines.

A shirt is arranged on the buck of the machine with the front of the collar band around the curved surface 3 of the body. The clamping member 4 is then moved on its pivot 7 by pressing upwardly on the weighted arm 8 moving the loop into a position opposed to the collar band so that when the loop is clamped it will hold the collar band between it and the surface 3 of the body 2. The operating member is then

2

pulled down into the position shown in Figure 3, thus pulling and tightening the clamp or the loop thereof, the sides of the loop moving inwardly against the springs 17. 5 During such downward movement of the handle the loop ordinarily would swing upwardly on its pivot due to the weight 8. In order to conveniently hold the loop from such swinging movement while the handle 10 is being operated, means is provided for temporarily relieving the loop of the effect of the weight arm 8. This means, as here shown, consists of a handle 19 pivoted on the handle 18 at 20, the handle 19 having 15 one arm extending under the arm 21 of the weighted arm 8. A spring 22 normally holds the lever 19 elevated. When the operator takes hold of the handle 18 to press it downwardly, he also presses down on the handle 19 thus lifting its front end into engagement with the arm 21 so that the weighted arm 8 cannot act to move the clamp 4 on its pivot. When the operating member 18 is swung into its final position, the tension of the loop will hold it in its 20 operative position.

What I claim is:—

1. A neck band clamp for shirt pressing machines comprising a body having a curved surface against which the front of the neck band is clamped, a clamp in the form of a loop having its opposite end portions pivotally mounted to enable the intermediate portion of the loop to swing into and out of position opposed to said surface and means tending to move the loop on its pivot and means for moving it bodily toward and from said surface. 30

2. A neck band clamp for shirt pressing machines comprising a body having a curved surface against which the front of the neck band is clamped, a clamp in the form of a loop having its end portions pivotally mounted to enable the intermediate portion 45 of the loop to swing into and out of position opposed to said surface and means tending to move the loop on its pivot and means for moving the loop pivotally toward and from said surface, and means for 50 preventing the pivotal movement of the clamp out of engagement with the collar band while the same is being moved bodily into clamping position.

3. A neck band clamp for shirt pressing machines comprising a body having a surface against which the front of the neck band is clamped, a carrier connected to the body, an operating member pivoted to the carrier in the rear of the body and a 55 clamping member having a portion coacting with said surface, said member being pivoted to the operating member on an axis parallel to, and in the rear of the axis of the operating member. 60

4. A neck band clamp for shirt pressing

machines comprising a body having a surface against which the front of the neck band is clamped, a carrier connected to the body, an operating member pivoted to the carrier, a clamping member pivoted to the operating member on an axis parallel to and in the rear of the axis of the operating member and having a portion for coacting with said surface, means tending to move the clamping member on its pivot out of clamping position, and means operable at will carried by the operating member for holding the clamping member from pivotal movement. 70

5. A neck band clamp for shirt pressing machines comprising a body formed with a surface against which the front of the neck band is clamped, a pivoted clamping member mounted to have a rectilinear movement toward and from said surface and an operating member connected to the clamping member to effect such rectilinear clamping movement, means acting on the clamping member tending to move it on its pivot, and means associated with the operating member operable at will for holding the clamping member from pivotal movement. 80

6. A neck band clamp for shirt pressing machines comprising a body having a surface against which the front of the neck band is clamped, and a pivoted operating lever for moving the clamping member rectilinearly toward and from said surface, the clamping member being pivotally mounted on the operating member on an axis eccentric and parallel to the axis of the operating member and having means tending to move it on its pivot out of operative position. 90

7. A neck band clamp for shirt pressing machines comprising a body having a surface against which the front of the neck band is clamped, a pivoted operating lever for moving the clamp rectilinearly toward and from said surface, the clamping member being pivotally mounted on the operating member on an axis eccentric to the axis of the operating member and having means normally tending to move it on its pivot out of operative position and means associated with the operating member for holding the clamping member from pivotal movement. 100

8. A neck band clamp for shirt pressing machines comprising a body having a surface against which the front of the neck band is clamped, and a pivoted operating member arranged with its pivot in the plane of the clamping member when the clamping member is opposed to said surface, the clamping member being pivoted to the operating member in the rear of the pivot of the operating member. 110

9. A neck band clamp for shirt pressing machines comprising a body having a surface against which the front of the neck band is clamped, a pivoted operating mem-

ber arranged with its pivot in the plane of the clamping member when the clamping member is opposed to said surface, the clamping member being pivoted to the 5 operating member in the rear of the pivot of the operating member, means tending to normally move the clamping member on its pivot out of operative position, and means associated with the operating member and 10 operable to hold the clamping member from pivotal movement.

10. A neck band clamp for shirt pressing machines comprising a body having a surface against which the front of the neck 15 band is clamped, a clamping member in the form of a flexible loop, movable toward and from said surface, the ends of the loop extending to the rear of said surface, the clamping member being pivoted at the rear 20 ends of the loop and movable on its pivot into and out of position opposed to said curved surface, and yielding means for spreading the loop.

11. A neck band clamp for shirt pressing 25 machines comprising a body having a surface against which the front of the neck band is clamped, a clamping member in the form of a flexible loop movable toward and from said surface, bearings to which the ends of 30 the loop are connected, and springs carried by the bearings, and pressing on the inner sides of the loop to spread the loop.

12. A neck band clamp for shirt pressing 35 machines comprising a body having an upright surface against which the front of the neck band is clamped, a carrier connected to the body, an operating member pivoted

to the carrier in the rear of the body, and a clamping member pivoted to the operating member on an axis parallel to and in the rear 40 of the axis of the operating member, the clamping member having a portion movable toward and from said surface, the pivot connecting the carrier and the operating member and the pivot connecting the clamping 45 member and the operating member being arranged with their axes in substantially a horizontal plane intersecting said surface.

13. A neck band clamp for shirt pressing machines comprising a body having a surface against which the front of the neck band is clamped, the body having a bracket extending upwardly therefrom, a link pivoted at its upper end to the bracket, a compression spring interposed between the link and the bracket, an operating member arranged in the rear of the link and pivoted to the lower end of said link, a clamping member in the form of a loop having its intermediate portion movable toward and from said surface, the end portions of the loop being pivoted to the operating member, a weighted arm associated with the clamping member and tending to move it on its pivot out of operative position, and a manually operable member carried by said operating member, and when operated coacting with the weighted arm to relieve the clamping member of the weight thereof.

In testimony whereof, I have hereunto 70 signed my name, at Syracuse, in the county of Onondaga, and in the State of New York, this 6th day of February, 1926.

ALBERT B. CLISSON.
